Electric Company, a corporation of New York

Filed June 30, 1966, Ser. No. 2,888

Term of patent 14 years

(Cl. D49—1)

FIG. 1

FIG. 2

FIG. 4

FIGURE 1 is a front perspective view of a dishwasher showing my new design;

FIGURE 2 is a front elevational view thereof, taken on an enlarged scale;

FIGURE 3 is a fragmentary side elevational view thereof; and,

FIGURE 4 is a fragmentary cross-sectional view thereof taken on the line 4—4 of FIGURE 2.

The dominant features of my design reside in the portions shown in full lines.

I claim:

The ornamental design for a dishwasher, substantially as shown and described.
